DANCING DOLL

Charles Lucius Lacour, P.O. Box 16, Simmesport, La.

Filed June 3, 1960, Ser. No. 60,838

Term of patent 14 years

(Cl. D34—4)

FIG. 1.

FIG. 2.

FIG. 3.

FIG. 4.

The dominant feature of my design resides in the portions shown in full lines. For convenience of illustration the broken line showing of the handle has been omitted in Figures 2 and 3, and shown fragmentarily in Figure 4.

I claim:

The ornamental design for a dancing doll, as shown and described.
